UNITED STATES PATENT OFFICE.

GEORGE A. PICKARD AND FRANK SLINGER, OF ALTRINCHAM, ENGLAND,
ASSIGNORS TO THE THORNTON-PICKARD MANUFACTURING COMPANY,
LIMITED, OF ALTRINCHAM, ENGLAND.

PHOTOGRAPHIC SHUTTER.

SPECIFICATION forming part of Letters Patent No. 781,156, dated January 31, 1905.

Application filed May 25, 1903. Serial No. 158,659. (Model.)

To all whom it may concern:

Be it known that we, GEORGE ARTHUR PICKARD and FRANK SLINGER, British subjects, and residents of Altrincham, in the county of 5 Chester, England, have invented certain new and useful Improvements in Photographic Shutters, of which the following is a specification.

This invention relates to improvements in 10 shutters of the type in which two pivoted leaves move backward and forward across one another to open and close the shutter, such as described in the specification of the prior English patent, No. 24,319 of 1899, and United States Patent No. 683,166. It 15 has been found in working the shutters hitherto constructed of this type that it has not been possible to obtain by pneumatic cylinders and pistons or other devices which have 20 been adopted an accurate or positive timing of the movement of the shutter-leaves across the aperture of the shutter.

This invention is designed to provide means 25 for more accurately adjusting the speed of travel of the shutter-leaves to the precise predetermined speed required; also, to provide better means for holding open the shutter any desired length of time for what is known as or termed a "time" exposure and to construct 30 a compact and easily-worked shutter with fewer parts.

It consists, essentially, in constructing the shutter with an additional or auxiliary spring to actuate the operating-disk which moves 35 the shutter-leaves, capable of being tightened up to the requisite degree to give the precise speed of travel desired to the shutter-leaves, and with an auxiliary adjustable sliding lever fitted to the releasing-lever provided with a 40 projecting catch to engage a detent upon the operating-disk when it is desired to stop the travel of the shutter for a time exposure, and also in placing the shutter-leaves between two fixed or stationary plates with slots therein, 45 through which guide-pins from the leaves project, and in slotting the lower plate to receive the pivots upon which the leaves of the iris-diaphragm rotate.

The invention will be fully described with reference to the accompanying drawings. 50

Figure 1 is an elevation of the shutter from the back with the case or cover removed and the parts in position preparatory to being set for an "instantaneous" exposure of the camera-lens; Fig. 2, a detached elevation of operating-disk A, the releasing-lever B, and adjustable auxiliary lever C in position at rest preparatory to being set for instantaneous exposure of the lens; Fig. 3, a detached elevation of the operating-disk A and levers B and C, 55 showing position when set for instantaneous exposure before being released; Fig. 4, a detached elevation of the operating-disk A and levers B and C, showing position they assume to release the shutters for instantaneous exposure, but before the shutters have begun to move; Fig. 5, a detached elevation of the releasing-lever B; Fig. 6, a detached elevation of the auxiliary lever C; Fig. 7, a detached elevation of the operating-disk A, the releasing-lever B, and the adjustable auxiliary lever C, 60 showing the position at rest of the auxiliary lever C when adjusted preparatory to being set for a time exposure; Fig. 8, a detached elevation of the operating-disk A and levers B and C, showing their position when set for a time exposure; Fig. 9, a detached elevation of the operating-disk A and levers B and C, showing their position after release of the shutter and during the period of time exposure; Fig. 10, a 65 front elevation of the shutter-case; Fig. 11, a detached elevation of modified form of releasing-lever B'; Fig. 12, a detached elevation of modified form of adjustable auxiliary lever C'; Fig. 13, a detached elevation similar to Fig. 2, 70 showing the modified forms of levers B' and C'; Fig. 14, a front elevation of shutter-case adapted for the modifications shown in Figs. 11, 12, and 13; Fig. 15, an elevation from back, showing the slotted plate G with the levers 3 and 4 removed; Fig. 16, an elevation from back, 75 showing the shutter-leaves 1 and 2 and the plate H with the plate G removed; Fig. 17, a sectional elevation, enlarged, through the leaves 1 and 2 and plates G and H. 80

The two shutter-leaves 1 and 2 are construct- 85

ed of the usual form, mounted upon or pivot-
ed to two links 3 and 4 and operated by a
transmitting-lever 5, connected by a spring 6
with the operating-disk A. The operating-
disk A is pivoted to rotate upon a stud *a* and
has a pin *a'* upon its face, to which are at-
tached the spring 6 and the auxiliary spring
*a*². The spring 6 is at its other end attached
to the transmitting-lever 5 of the shutter-
leaves 1 and 2 and the second or auxiliary
spring *a*² to a drum D, upon which it is ca-
pable of being wound up. By rotating the
drum D the auxiliary spring is wound around
its periphery and stretched, thereby increas-
ing the tension of the spring, and by rotat-
ing it back in the reverse direction the spring
is released and the tension decreased. By
tightening the auxiliary spring *a*² the move-
ment of the operating-disk A can be acceler-
ated to any degree, the extent of the rota-
tion of the drum D determining the amount.
When the shutter-leaves 1 and 2 are desired
to travel at a slow speed—say one twenty-
fifth of a second—the auxiliary spring is prac-
tically inoperative; but when desired to travel
at a higher speed than, say, one twenty-fifth—
say from one-thirtieth to one one-hundred-
and-fiftieth of a second—the auxiliary spring
is wound less or more upon the drum D and
stretched accordingly. The drum D is ro-
tated by a knob D' on the outside of the cas-
ing and is provided with a pointer *d*, travel-
ing over an index or indicator plate *d'*. The
pin *a'* of the operating-disk A, to which the
springs 6 and *a*² are attached, also serves to
engage the transmitting-lever 5 and operates
it in the direction to expose or uncover the
lens, the spring 6 drawing it back again.
From the other side or face of the disk A a
pin *a*³ projects, which engages with a shoul-
der or projection *b* on the releasing-lever B,
by which the disk and operative parts are
held stationary after being set until the re-
leasing-lever B is moved and the shoulder *b*
raised out of the path of the pin *a*³. On the
same face of the disk A is a second detent or
pin *a*⁴, by which the disk is stopped in its
travel and held during a time exposure.

The releasing-lever B is placed behind the
operating-disk A and is pivoted to the casing,
preferably upon the same stud *d* as the spring-
tightening drum D, and is placed to lie be-
tween the releasing-pin *a*³ on the under side
of the operating-disk A and the pin or center
a, upon which the disk A rotates, so that as
it is moved to release the disk it is moved to-
ward the center thereof.

To the releasing-lever B is fitted an adjust-
able sliding auxiliary lever C, the position of
which relatively to the releasing-lever B is ca-
pable of alteration and adjustment by an ec-
centric or eccentric-pin E or other device.
The auxiliary time-lever C is provided with a
catch or projection *c* (projecting in an oppo-
site direction to that on the releasing-lever)

to engage with the second detent or pin *a*⁴ on
the operating-disk. The traversing or slid-
ing of the auxiliary time-lever C over the re-
leasing-lever B puts the projection *c* into or
out of the path of the second pin or detent *a*⁴ 70
on the releasing-disk. Consequently when set
for a time or prolonged exposure the raising
or movement of the releasing-lever B to dis-
engage it from the releasing-pin *a*³ on the disk
A at the same time raises the catch or pro-
jection *c* of the auxiliary lever C into the di-
rect path of the second pin or detent *a*⁴ 75
on the disk A and stops the rotation of the disk A
at the point when the shutter is open, holding
the shutter open until the releasing-lever B 80
is dropped or moved back again. (See Fig.
9.) When the auxiliary lever C is moved by
the eccentric E into the reverse position,
Figs. 3 and 4, the catch or projection *c* there-
on is moved to one side and out of the path 85
of the second detent or pin *a*⁴ upon the releas-
ing-disk, thus allowing of a rapid or instan-
taneous exposure. The eccentric E for actu-
ating the auxiliary lever is preferably upon
the same spindle *d* and operated by the same 90
knob D' as the drum D for tightening the aux-
iliary spring *a*², the eccentric-pin E being so
placed that it moves the auxiliary lever C into
position for a time or prolonged exposure af-
ter the auxiliary spring has contracted and 95
all tension thereof is relieved. By this ar-
rangement when a time or prolonged expo-
sure is being effected the parts are traveling
at a comparatively slow speed, because the
second or auxiliary spring is slack and non-
effective. (See Figs. 2 to 10.) In an alter-
native arrangement an eccentric E' may be
placed at the other end of the auxiliary lever
C and be operated by a separate or independ-
ent knob E'. (See Figs. 11 to 14.) The le-
vers are adjustably held together by pins *c'*,
projecting from one entering slots in the other.

On the face of the case a dial-plate *d'* is fitted,
inscribed with fractional parts of a second
to indicate the rate of travel of the disk A, and
shutter-leaves 1 and 2 at the different degrees
of tension of the auxiliary spring *a*², and an
index-pointer *d*² is affixed to the knob D' or
spindle *d* of the drum D to show the amount
of the spring *a*² wrapped upon the drum and 110
the consequent speed at which the apparatus
is set to travel. On Fig. 14 a second knob
E², with index-plates *e*² and pointer *e*³, indicates,
whether the apparatus is set for time or in-
stantaneous exposure.

The shutter-leaves 1 and 2 are placed be-
tween two fixed or stationary plates G and H,
between which they move to and fro. The
plate G is provided with curved slots *g*, and
the plate H is provided with curved slots *h*. 115
From the leaves 1 and 2 guide-pins *g'* project
to either side and enter the curved slots *g*
and *h*, which guide the leaves in their travel
across the aperture and cause them to move
perfectly evenly and freely backward and for- 120
125
130

ward. The links or levers 3 and 4, which connect the leaves 1 and 2, are pivoted to the plate G, thereby insuring a steady and even action. The plate H is also slotted with a number of radial slots h' to receive the pins or pivots m of the leaves M of the iris-diaphragm.

An air-bulb P is placed below the end of the releasing-lever B to raise or move it and is connected to an air-tube p . R is a hand-lever, also for operating the releasing-lever B.

What we claim as our invention, and desire to protect by Letters Patent, is—

1. In a photographic shutter, the combination with the shutter-leaves 1 and 2, the links 3 and 4 to which they are pivoted, the transmitting-lever 5, spring 6 connected thereto, and an operating-disk A, of an auxiliary driving-spring a^2 connected by one end to the operating-disk, a drum D to which the other end of the spring is attached and upon which it may be wound, a knob D' to rotate the drum to increase or decrease the tension on the spring, and a releasing-lever B which engages 25 a projection on the disk A, substantially as described.

2. In a photographic shutter, the combination with the shutter-leaves 1 and 2, the links 3 and 4, to which they are pivoted, the transmitting-lever 5, spring 6 connected thereto, and an operating-disk A, of an auxiliary driving-spring a^2 connected by one end to the operating-disk, a drum D to which the other end of the spring is attached and upon which it 35 may be wound, a knob D' to rotate the drum to increase or decrease the tension on the spring, projection a^3 and detent a^4 on the operating-disk, a releasing-lever B provided with a catch b to engage the projection a^3 on 40 the disk, an auxiliary adjustable lever C mounted upon the releasing-lever B and provided with a catch c to engage the detent a^4 on the disk A, and means for moving and adjusting the position of the auxiliary lever C, 45 substantially as described.

3. In a photographic shutter, the combination with the shutter-leaves 1 and 2, the links 3 and 4 to which they are pivoted, the transmitting-lever 5, spring 6 connected thereto, 50 and an operating-disk A, of an auxiliary driving-spring a^2 connected by one end to the operating-disk, a drum D to which the other end of the spring is attached and upon which it may be wound, a knob D' to rotate the drum to increase or decrease the tension on the 55 spring, projection a^3 and detent a^4 on the operating-disk, a releasing-lever B provided with a catch b to engage the projection a^3 on the disk, an auxiliary adjustable lever C mounted 60 upon the releasing-lever B and provided with

a catch c to engage the detent a^4 on the disk A, and an eccentric-pin E affixed to the drum D to adjust the position of the auxiliary lever C to bring it into position either for "time" or instantaneous exposure as desired, substantially as described.

4. In a photographic shutter the combination with the shutter-leaves 1 and 2, the links 3 and 4 to which they are pivoted, the transmitting-lever 5, spring 6 connected thereto, and an operating-disk A, of an auxiliary driving-spring a^2 , connected by one end to the operating-disk, a drum D to which the other end of the spring is attached and upon which it may be wound, a knob D' to rotate the drum to increase or decrease the tension on the spring projections a^3 and detent a^4 on the operating-disk, a releasing-lever B provided with a catch b to engage the projection a^3 on the disk, an auxiliary adjustable lever C mounted 65 upon the releasing-lever B and provided with a catch c to engage the detent a^4 on the disk A and means for moving and adjusting the position of the auxiliary lever C, and the two plates G and H between which the leaves 1 and 2 of the shutter move to and fro provided with curved slots g and h to guide the leaves 1 and 2 and with radial slots h' to guide the leaves of an iris-diaphragm substantially as described.

5. In a photographic shutter, the combination with the shutter-leaves 1 and 2, the links 3 and 4, to which they are pivoted, the transmitting-lever 5, spring 6 connected thereto, and an operating-disk A, of an auxiliary driving-spring a^2 connected by one end to the operating-disk, a drum D to which the other end of the spring is attached and upon which it may be wound, a knob D' to rotate the drum to increase or decrease the tension on the spring projection a^3 and detent a^4 on the operating-disk, a releasing-lever B provided with a catch b to engage the projection a^3 on the disk, and auxiliary adjustable lever C mounted 90 upon the releasing-lever B and provided with a catch c to engage the detent a^4 on the disk A and means for moving and adjusting the position of the auxiliary lever C, and the two plates G and H between which the leaves 1 and 2 of the shutter move to and fro provided with curved slots g and h to guide the leaves 1 and 2 and with radial slots h' to guide the leaves of an iris-diaphragm substantially as described.

In witness whereof we have hereunto signed our names, in the presence of two subscribing witnesses, this 12th day of May, 1903.

G. A. PICKARD.
